UNITED STATES PATENT OFFICE.

EMANUEL O. GOLDSMITH, OF MEMPHIS, TENNESSEE.

HEEL-GUARD AND TOE-CLIP.

1,387,385.

Specification of Letters Patent.

Patented Aug. 9, 1921.

Application filed February 9, 1921. Serial No. 443,577.

To all whom it may concern:

Be it known that I, EMANUEL O. GOLDSMITH, a citizen of the United States, residing at Memphis, in the county of Shelby and State of Tennessee, have invented certain new and useful Improvements in Heel-Guards and Toe-Clips; and I do hereby declare the following to be a full, clear, and exact description of the invention, such as will enable others skilled in the art to which it appertains to make and use the same.

The present invention relates to improvements in heel guards and toe clips for shoes, and an object thereof is to provide an anti-skid attachment for shoes that may be readily applied to the shoe and as quickly removed therefrom, and while in place serves efficiently to prevent the wearer from slipping on ice or other slippery surfaces.

Another object of the invention is to provide a simple and inexpensive construction of the above character which is applied to a shoe and adjusted thereon somewhat in the fashion of ice skates, and which will accommodate and adapt itself to the various styles and sizes of shoes so as to make the device substantially of standard construction capable of being applied to various cases.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 shows in dotted lines a side elevation of a shoe with an improved heel guard and toe clip applied thereto as constructed in accordance with the present invention;

Fig. 2 is a top plan view of the device with the shoe removed;

Fig. 3 is a bottom plan view of the device;

Fig. 4 is a transverse sectional view taken on the line 4—4 in Fig. 2; and

Fig. 5 is a similar view taken on the line 5—5 also in Fig. 2.

Referring more particularly to the drawings, 1 illustrates in dotted lines the configuration of a shoe to which the invention is to be applied. According to the invention I provide an auxiliary sole 2 which may be of leather, rubber, or other suitable material, 55 to which is attached a number of studs or

calks 3 as by riveting them in rows to the auxiliary sole. This auxiliary sole 2 is applied beneath the sole of the shoe 1, a layer of oil skin being preferably interposed between the two to avoid the entrance of water 60 to the shoe.

The auxiliary sole 2 is held in place by the use of substantially U-shaped clips 4 and 5 which are designed to fit about the edges of the auxiliary sole 2 and the extension sole of 65 the shoe. The clips 4 and 5 are curved in plan as indicated in Figs. 2 and 3, and similarly the edges of the auxiliary sole 2 are curved to correspond so that a longitudinal shifting movement of the auxiliary sole will 70 be prevented. The side or vertical walls of the clips 4 and 5 are provided with grooves 6 and 7 to receive the end portions 8 and 9 of a wire employed to bind the clips in place. The extremities of the wire which terminate 75 at the sides of the tip of the shoe are connected together by a coil spring 10 which fits about the shoe tip just above the extension sole, and this coil spring adapts and accommodates itself to various sizes and 80 styles of shoes and is either extended or contracted according to such shapes and styles, and it is useful in allowing the clips 4 and 5 to adjust themselves correctly to positions about the extension sole of the shoe to which 85 the device is at any time attached.

The heel of the shoe is incased in a heel cup 11 made preferably of metal, aluminum, being light, serving admirably for this purpose. As shown in Fig. 4 the heel cup is 90 provided with an inturned flange 12 along its lower edge to receive and bind in place the supplemental heel 13 which carries the calks or studs 14. Along its upper edge in a similar manner the heel cup 11 is formed 95 with an inturned shoulder 15 adapted to engage in the rand of the shoe.

A groove 16 is made about the wall of the heel cup 11 and receives the opposite end portions of the wire which passes about the heel cup and draws the walls of the same closely about the heel of the shoe. The ends of the wire may be twisted at the back of the heel. Beneath the instep the wire is crossed, as best shown in Figs. 2 and 3, and 100 a pair of clamps or blocks 18 are fitted at opposite sides of the crossed portion of the wire, a bolt 19 going freely through the blocks and having a head at one end and a lever 21 at its other end pivoted as indicated 110

at 22 and provided with a cam 23 adapted to bear directly against the adjacent block 18 and acting to draw the two blocks or clamps together upon the wire.

Obviously any other form of clamping means may be employed. The heel guard 20, made of aluminum or other material, is affixed in any suitable manner to the heel cup 11 and projects about the rear portion 10 and sides of the heel to form a guard for the trousers or skirt preventing the same from getting down into the mire or other undesirable places.

In use, the device is applied to the shoe in 15 the manner indicated in Fig. 1 where it forms an effective means to avoid the wearer slipping or falling upon ice or glassy surfaces. The auxiliary sole 2 is attached by placing it against the shoe sole with a piece 20 of oil skin therebetween, the clips 4 and 5 being then pressed into place and the wire extended thereabout. The spring 10 will allow of the clips being separated so as to attach and remove them, and when put in 25 place the spring 10 will contract and hold the parts against accidental detachment. The adjusting screw 19 may be resorted to only whenever it becomes necessary to bind the wire more tightly for shoes of a smaller 30 size or to allow the wire to extend itself to fit larger shapes.

It is obvious that various changes and modifications may be made in the details of construction and design of the above specifically described embodiment of this invention 35 without departing from the spirit thereof, such changes and modifications being re-

stricted only by the scope of the following claims.

What is claimed is:

1. A heel guard and toe clip comprising 40 guard means fitting the heel of a shoe, an auxiliary sole fitting beneath the shoe sole, coupling members engaged with the auxiliary and shoe soles, flexible securing means 45 engaging with the guard means and said coupling members, and resilient means across the toe of the shoe connecting the ends of the flexible securing means.

2. A heel guard and toe clip comprising 50 an auxiliary heel fitting beneath the heel of the shoe, a cup engaged about the shoe heel and the edge and a portion of the under face of the auxiliary heel and having a groove therein, a guard plate on the cup, flexible 55 securing means passing about in the groove, and an auxiliary sole under the shoe sole held in place by said flexible securing means.

3. A heel guard and toe clip comprising 60 an auxiliary sole fitted beneath the shoe sole and having studs projecting therefrom, U-shaped clips fitted loosely over the extension sole of the shoe and said auxiliary sole and provided with grooves, a heel cup fitting over the heel of the shoe and provided with 65 anti-skid studs, said heel cup provided with a groove therearound, a wire passing about in the groove in said heel cup and clips, a coil spring connecting the ends of the wire across the toe of the shoe, and an adjusting 70 device beneath the instep through which the wire is crossed, substantially as described.

EMANUEL O. GOLDSMITH.
